UNITED STATES PATENT OFFICE.

CHARLES A. BUSH, OF OSHKOSH, WISCONSIN, ASSIGNOR TO OSHKOSH MANUFACTURING COMPANY, OF OSHKOSH, WISCONSIN, A CORPORATION OF WISCONSIN.

MIXING-MACHINE.

1,211,539.

Specification of Letters Patent.

Patented Jan. 9, 1917.

Application filed February 6, 1915. Serial No. 6,462.

To all whom it may concern:

Be it known that I, CHARLES A. BUSH, a citizen of the United States, and resident of Oshkosh, in the county of Winnebago and 5 State of Wisconsin, have invented new and useful Improvements in Mixing-Machines, of which the following is a description, reference being had to the accompanying drawings, which are a part of this specification.

10 The invention relates to mixing machines. In mixing machines of large capacity it is necessary to provide means for lifting the discharging chute by power.

15 The object of the present invention is to permit the raising and lowering of the chute by mechanism driven from the same shaft as that which drives the revolving mixing chamber.

20 The invention further designs to provide a new and improved form of power operated mechanism for operating the discharging chute of a mixing machine.

25 The invention consists in the several features hereinafter set forth and more particularly defined by claim at the conclusion hereof.

30 In the drawings, Figure 1 is an end view of a mixing machine equipped with the devices embodying the invention; Fig. 2 is a side view thereof (parts being broken away); Fig. 3 is a detail view of the power operating mechanism as seen from the side adjacent the machine (parts being shown in section).

35 The machine to which the improvements are applied is of usual construction comprising a mixing chamber 4 mounted upon the frame 5 and adapted to be driven by a chain (not shown) operatively connecting it to a 40 sprocket 6 mounted upon a shaft 7 journaled in bearings 8, 9 and 10 formed in the support 11 mounted upon the frame 5. The shaft 7 has also mounted thereon a gear 13 around which a sprocket chain (not shown)

45 passes leading from the engine mechanism whereby the shaft 7 is rotated. This is all of well known construction and power operating means are provided for operating the discharging chute from the power shaft 50 7 at predetermined intervals. This power operating means comprises a worm 14 loosely mounted upon the power shaft 7, means for operatively connecting said worm 14 to rotate with said shaft, a gear wheel 15

55 in mesh with the worm 14 and mounted upon

a shaft 16 journaled in bearings on the support 11. This shaft carries a crank arm 17 whose free end is pivotally connected to one end of a link 18 by a pin 19. The other end of the link is, pivotally connected to the 60 forked end of a crank 20 by a pin 21 said crank 20 being mounted upon a longitudinally extending shaft 22 journaled in bearings in uprights 23 of the frame 5. This shaft 22 carries a yoke member 24 between 65 the bearings on the uprights 23 and a lever arm 25 is pivotally secured at one end to the arms of said yoke member by a pin 26. The other end of the lever 25 is pivotally secured by a pin 26' to a plate 27 which is fastened 70 to the chute 28. The chute 28 is pivotally secured to the slop guard plates 29 by mechanism shown but not described which plates are secured to the uprights 23 by fastening means passing therethrough and through 75 lugs 30 on said plates.

From the above description it follows that when the shaft 7 is rotated the worm 14 being connected will rotate the gear wheel 15, shaft 16 to turn the crank 17 which will 80 move the link 18 and crank 20 to turn the shaft 22 and consequently the yoke member 24 which in turn will move the lever arm 25 upwardly or downwardly and consequently the end chute 28 to which it is connected 85 and for every one half revolution of the worm gear the discharge chute is changed from a mixing to a discharging position.

The means for operatively connecting the worm 14 to the shaft 7 comprises a friction 90 disk 31 secured thereto and having an annular recess 32 therein adapted to receive an annular friction block 33 suitably secured to a disk 34 which is keyed to a sleeve 35 and slidably thereon, the sleeve being mounted fast upon the shaft 7. The sleeve 35 has a threaded end 36 upon which a threaded collar 37 is mounted and a dog 38 is pivotally secured at the lower portion of the collar. The dog 38 is in engagement with the 100 side of the disk 34 and the movement of the dog will result in a longitudinal movement of the disk 34 to bring the friction block 33 into engagement with the friction disk 31. This movement of the dog is regulated by a 105 sliding collar 39 mounted upon the shaft 7 and carrying a collar 40 in threaded engagement therewith and connected by a link 41 which is pivotally secured to the collar 39 to dog 38. The collar 39 is also provided with 110

a groove 42 for receiving a forked lever (not shown) of usual construction to reciprocate said collar upon the shaft to thereby move the dog into or out of engagement with the disk 34 to operate the clutch and thereby connect the worm to the drive shaft 7.

The operation of the device in brief is as follows:—The operator throws in the clutch comprising the friction disk 31 and block 33 thereby causing the worm 14 to rotate with the power shaft 7. The rotation of the worm 14 as previously described causes the rotation of the shaft 22 and the linkage connected to said shaft and the chute 28 causes the chute to move upwardly and downwardly for each revolution of the worm gear 15.

In mixing machines of the character described, it is often desired to discharge from the mixing chamber small quantities of material, such as wheel-barrow loads, at regular intervals, instead of discharging all of the material at one time. This is easily accomplished with the herein described construction, by simply throwing in the clutch 25 to the power shaft and allow the chute mechanism to operate continuously. Thus as long as the clutch is in engagement, the crank-arm 17 will continue to rotate and consequently reciprocate the links and arms connected to the chute, and the chute will move continuously from one inclined position to the other. Owing to the worm-gearing the movements of the chute are slow, hence the discharge from the drum or chamber will commence shortly after the chute reaches a horizontal position in its downward movement, and will continue to dis-

charge from that time until it descends to full discharge position and returns to the initial discharging position. The worm-gearing for operating the chute also forms a self-locking mechanism, whereby the chute will retain any adjusted position when the clutch is disengaged.

The invention thus exemplifies a power 45 operated mechanism for operating the discharging chute connected to the drive shaft and means for throwing said power operated means into or out of engagement with the drive shaft. 50

What I claim as my invention is:—

In a mixing machine, a mixing chamber, a drive shaft mounted for continuous rotation in parallel relation to said mixing chamber, a discharge chute pivoted adjacent to 55 one end of said mixing chamber, a rock-shaft having oppositely extending crank-arms mounted below said chute and at right-angles to said drive shaft, a worm mounted loosely on said drive-shaft, a clutch for connecting said worm to said drive-shaft, a horizontally reciprocating link operated by 60 said worm to operate said rock-shaft, and a vertically reciprocating link connected to said chute and operated by said rock-shaft 65 for reciprocating said chute vertically to discharging and non-discharging positions.

In testimony whereof, I affix my signature, in presence of two witnesses.

CHARLES A. BUSH.
